(57) **CLAIM**

The ornamental design for a plant cover, as shown and described.

DESCRIPTION

FIG. 1 is a top view of a first embodiment of a plant cover illustrating the new design;

FIG. 2 is a front view of the plant cover of FIG. 1;

FIG. 3 is a perspective view of the plant cover of FIG. 1;

FIG. 4 is a top view of a second embodiment of the plant cover illustrating the new design;

FIG. 5 is a front view of the plant cover of FIG. 4;

FIG. 6 is a perspective view of the plant cover of FIG. 4;

FIG. 7 is a top view of a third embodiment of the plant cover illustrating the new design;

FIG. 8 is a front view of the plant cover of FIG. 7;

FIG. 9 is a perspective view of the plant cover of FIG. 7;

FIG. 10 is a top view of a fourth embodiment of the plant cover illustrating the new design;

FIG. 11 is a front view of the plant cover of FIG. 10; and,

FIG. 12 is a perspective view of the plant cover of FIG. 10. In the drawings, the broken lines depict portions of the plant cover that form no part of the claimed design.

1 Claim, 7 Drawing Sheets
